FIG. 5

UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

SHEDDING MECHANISM FOR LOOMS.

Application filed July 31, 1925. Serial No. 47,229.

To all whom it may concern:

Be it known that I, CARL D. BROWN, a citizen of the United States, and a resident of Hopedale, in the county of Worcester and 5 State of Massachusetts, have invented an Improvement in Shedding Mechanisms for Looms, of which the following description, in connection with the accompanying drawings, is a specification, like characters on the 10 drawings representing like parts.

This invention relates to shedding mechanisms for looms, and more particularly to means for disconnecting the power from the shedding mechanism to permit hand operation 15 of the shedding mechanism for finding the pick or to position the heddle frames for piecing up or other causes.

In accordance with the present invention, the heddle frames which control the warp 20 threads during shedding are connected to jack levers preferably located at the side of the loom and pivotally mounted between their ends for operation by the jack lever operating cams also preferably located at the 25 same side of the loom as the jack levers, such cams being actuated from a driving shaft, including a clutch, whereby the driving power may be disconnected from the cams to 30 permit manual operation of the cams for finding the pick, or for other purposes, by means of manual manipulation through a reach shaft.

The present invention will best be understood from the following description and the 35 accompanying drawings of one good form thereof.

In the drawings:

Fig. 1 is a perspective view of a loom containing the present invention and with some 40 of the parts broken away;

Fig. 2 is a front view of a loom, showing more particularly the features associated 45 with the present invention;

Fig. 3 is an enlarged detail showing the weighted trip lever for operating the clutch;

Fig. 4 is an enlarged view showing the clutch and driving connections between the driving shaft and cams; and

Fig. 5 is an enlarged detail in side elevation of portions of the loom arch and the connection of the reach shaft with the manually operable means thereof.

The loom frame 1 may be of usual con-

struction and as shown the loom is of the automatically replenishing type wherein the 55 hopper 2 is supplied with filling carriers 3 in order to supply the shuttle automatically with fresh filling at times. The transerrer 4 has connected thereto the dog 5 for transferring a fresh supply of filling to the shuttle, but the details of such mechanism are not herein further illustrated because they 60 form no essential part of the present invention.

Extending from the loom side and preferably secured to the upright 6 are the brackets 7 to which are preferably mounted at 8 between their ends jack levers 9. The upper and lower end portions 10 and 11 of the jack levers are connected to the several heddle 70 frames, and as shown, such connection is afforded by a flexible means, such as the straps 12 which pass from the lower end of the jack levers about the pulley 13 and are connected to the bar 14 which is itself connected 75 to one of the heddle frames 15, it being understood that the several jack levers are connected to the respective heddle frames in substantially similar manner between their 80 ends.

Extending between the uprights 6 of the loom frame is the loom arch 16 on which are mounted the guide pulleys 17 and 18, over which pass straps 19 and 20 which are secured to the associated heddle frame. The 85 straps 19 and 20, as shown, are connected to the upper end portion 10 of the jack levers 9.

Mounted at the side of the loom adjacent the jack levers are a series of jack operating cams, and in the present instance of the invention such cams find their support on a stand 21 extending from the loom side. Between suitable bearings on the stand 21 extends the cam supported shaft 22 on which the series of cams 23, one for each jack 95 lever, is mounted. The cams 23 are preferably secured to the shaft 22 and such shaft carries a bevelled gear 24 secured thereto.

The cams for operating the jack levers are driven from a going part of the loom and, as shown, the driving shaft 25 extends transversely of the loom frame and carries a toothed gear 26 preferably located outside of the shaft bearing 27. Mounted in parallel relation with the driving shaft 25 is the 100 transmitting shaft 28 which may be properly

supported in suitable bearings 29, 30, one of which may be secured to the loom frame and the other to the stand 21.

Secured to the transmitting shaft 28 is a gear 31 which is in constant mesh with the companion gear 26 on the driving shaft. Loosely mounted on the transmitting shaft 28 is the bevelled gear 32 which meshes with the bevelled gear 24 hereinbefore described, and such gear 32 is held from longitudinal movement on the transmitting shaft, although free to rotate relative thereto.

Between the gear 31 and the bevelled gear 32 is the clutch member 33 splined to the shaft 28 and having a circular opening 34 which is engaged by the pins 35 extending from the embracing arms 36 of a yoke 37 pivotally mounted at 38 on a bracket or support 39.

The clutch member 33 and the hub of the bevelled gear 32 are each provided with interengaging clutch members 40 and 41 which are constructed and arranged so that the clutch members can be engaged only when the jack lever operating cams and the driving shaft are in predetermined relation. As shown, the clutch member 33 has a projecting portion which constitutes one-half of the face of the clutch member, while the cooperating clutch member on the hub of the loose gear 32 has a similar half portion, the result being that the clutch members can be moved into engagement only when the projecting portion of each is opposite the recess in the other, and as the bevelled gear 32 is associated with the jack lever operating cams 23 through the gear 24, it follows that the clutch members can be engaged only when the jack lever operating cams and perforce the jacks and the driving shaft are in predetermined relation, such predetermined relation being that assumed when the clutch members were disengaged.

The yoke member 37 is connected at 42 to the reach rod 43 which extends upwardly and has an arm 44 pivotally mounted at 45 to the horizontal arm 46 of a bell crank lever pivoted at 47 to the upright 6 of the loom frame. The other member 48 of the bell crank lever is pivotally connected at 49 with a link 50 having its opposite end connected at 51 to the lower portion of a weighted hand lever 52 pivotally mounted at 53 on the upright 6. Instead of mounting the levers upon the upright 6, as suggested, it has been found desirable to interpose between the levers and the upright 6 a bracket 54 formed as a plate which may be adjustably connected to the upright 6 by a bolt 55 engaged in a slot 56 formed in the plate.

As hereinbefore mentioned, the hand lever 52 is weighted and may be provided with a weighted end 57 such that when the hand lever 52 is thrown into position for disconnecting the clutch members hereinbefore de-

scribed, the weight 57 will maintain the hand trip lever 52 in position with the clutch members disengaged. If desired, a stop 58 may be utilized to limit the swinging movement of the hand trip lever 52 to and from its clutching and unclutching positions.

Mounted upon the loom arch 16 is manual means for operating the jack lever cams when the clutch hereinbefore described has been unclutched. In the present instance of the invention, the loom arch is provided with bearings 59 in which is mounted the shaft 60 having a bevelled gear 61 which engages a bevelled gear 62 mounted on the reach shaft 63. The reach shaft 63 extends diagonally downward from the loom arch and is supported at its upper end in a bearing 64, while at its lower end it finds support in a bearing 65 carried by the bracket 39, and below the bearing 65 the reach shaft 80 is provided with a bevelled gear 66 which meshes with the bevelled gear 24 secured to the cam operating shaft 22.

The shaft 60, hereinbefore described, is provided with manual means for turning the shaft and perforce the reach shaft and jack lever operating cams when the clutch members 40 and 41 are disengaged.

As indicated in Fig. 5, the shaft 60 is provided with a collar 67 which is secured thereto by a set screw 68, and such collar has clutch teeth 69. Loosely mounted upon the shaft 60 is the hand wheel 70, the hub portion 71 of which is also provided with a clutch member 72 adapted to engage the projecting clutch portion 69 of the collar 67, and interposed between the hub of the hand wheel and collar 67 is a spring 73 normally holding the clutch members disengaged but permitting engagement thereof when the hand wheel is moved inwardly in opposition to the spring 73.

Should it become necessary at any time to stop the loom to find the pick or for piecing up broken ends or any other reasons connected with the formation of the fabric, the weaver may disengage the clutch members 40 and 41 by manual operation of the hand trip lever 52, thereby disconnecting the jack lever operating cams from the power driving means, and since the hand trip lever 52 is weighted, as described, it will act to hold the parts in this position when once the clutch members are disengaged. The loom having thus been stopped and the clutch members 40 and 41 disengaged, the weaver may manipulate the hand wheel 70 which is preferably located at the same side of the loom as the trip lever 52, and thereby turn the reach shaft 63 and operate the jack lever operating cams to find the pick or piece up broken ends or for other purposes. When the defect in the weaving operation has been cured, however, it is desirable that the heddle frames shall assume the

- same relative position as they had when the loom was stopped and the clutch members disengaged, before the power is thrown on to actuate the heddle frames. This is conveniently effected by forming the clutch members 40 and 41 as hereinbefore described, so that they can only be engaged, after having been disengaged, when the cams and power shaft have been moved to their former relative positions, so that in starting up the loom the parts are in position to proceed with weaving perfect cloth. 5
- What is claimed is:
1. In loom shedding mechanism, the combination of jack levers, heddle frames, means connecting the heddle frames and jack levers, cams for operating the jack levers in the formation of sheds, an operating shaft for the cams, gearing connections between the operating shaft and cams including a clutch, a hand operated trip lever for disconnecting the clutch members and interrupting the driving connection with the operating shaft to free the cams, a reach shaft having gearing connection with the cams and extending to the loom arch, a manually operable shaft on the loom arch having gearing connection with the reach shaft, and a hand wheel disposed at the same side of the loom as the trip lever for operating the reach shaft when the trip lever has been manually operated to disconnect the clutch members. 10
2. In a loom shedding mechanism, the combination of jack levers, heddle frames, flexible connections between the upper and lower ends of the jack levers and heddle frames, jack lever operating cams, a driving shaft for the cams, gearing connection between the driving shaft and cams including a clutch, the members of which are engageable only when the cams are in the same position they were when the clutch members were disengaged, a hand operated trip lever for disconnecting and connecting the clutch members, a reach shaft having gearing connection with the cams and extending to the loom arch, and a hand wheel at the same side of the loom as the trip lever for operating the reach shaft when the clutch members have been disengaged. 15
3. In a loom shedding mechanism, the combination of jack levers pivotally mounted on the loom frame between the ends of the levers, heddle frames, flexible connections between the upper and lower ends of the jack levers and heddle frames, jack lever operating cams, a driving shaft for the cams, gearing connection between the driving shaft and cams including a clutch, the members of which are engageable only when the cams are in the same position they were when the clutch members were disengaged, a hand operated trip lever for disconnecting and connecting the clutch mem- 20
- bers, a reach shaft having a gearing connection with the cams and extending to the loom arch, and a hand wheel at the same side of the loom as the trip lever for operating the reach shaft when the clutch members have been disengaged. 25
4. In a shedding mechanism for looms, the combination of a series of heddle frames, jack levers connected to the heddle frames, jack lever operating cams, a driving shaft for the cams, gearing connections between the said shaft and cams including a clutch, the members of which are provided with interlocking portions constructed and arranged for driving engagement only in a predetermined relation of the driving shaft and cams that power operation of the cams can be effected by the clutch only when the heddle frames are in the same relative position they occupied when the clutch members were disengaged, a hand operated trip lever for operating the clutch, a reach shaft, gearing connections between the reach shaft and cams, and a hand wheel on the loom arch for manually turning said cams when the clutch members are disengaged. 30
5. In a shedding mechanism for looms, the combination of a series of heddle frames, jack levers connected at their upper and lower ends to the top and bottom of the heddle frames, jack lever operating cams, a driving shaft for the cams, gearing connections between said shaft and cams including a clutch, the members of which are provided with interlocking portions constructed and arranged for driving engagement only in a predetermined relation of the driving shaft and cams that power operation of the cams can be effected by the clutch only when the heddle frames are in the same relative position they occupied when the clutch members were disengaged, a hand operated trip lever for operating the clutch, a reach shaft, gearing connections between the reach shaft and cams, and a hand wheel on the loom arch for manually turning said cams when the clutch members are disengaged. 35
6. In a shedding mechanism for looms, the combination of a series of heddle frames, jack levers pivotally mounted between their ends at the side of the loom frame and connected at their upper and lower ends respectively to the top and bottom of the heddle frames, a series of jack lever operating cams at the side of the loom frame for operating the jack levers, a driving shaft, gearing connections between the driving shaft and cams including a clutch, a trip for operating the clutch, comprising a hand lever at the side of the loom, a bell crank lever adjacent thereto, a link connecting the bell crank lever and hand lever, a reach rod connected to the bell crank lever, a yoke connected to the reach rod for operating 40
- 70

- the clutch, a reach shaft between the cams and loom arch, and a hand wheel for operating the reach rod and cams when the clutch is disengaged.
- 6 7. In a shedding mechanism for looms, the combination of a series of heddle frames, jack levers connected to said heddle frames, a series of cams at the side of the loom for operating the jack levers, a driving shaft, 10 gearing connections between the driving shaft and cams including a clutch, a trip for the clutch having a weighted hand piece pivotally mounted, a bell crank and reach rod connection between the weighted hand piece and clutch that the weighted hand piece may maintain the clutch disengaged when the hand piece is manually moved to clutch disengaging position, a reach shaft 15 geared to the cams, and a hand wheel on the loom arch for operating the reach shaft 20 while the clutch is held disengaged by the weighted hand piece.

In testimony whereof, I have signed my name to this specification.

CARL D. BROWN.
